Primary Examiner — Vy N Koenig*Assistant Examiner* — Qiawen W Wiechert(74) *Attorney, Agent, or Firm* — Kolitch Romano Dascenzo Gates LLC(57) **CLAIM**

The ornamental design for a kitchen island, as shown and described.

DESCRIPTION

FIG. 1 is a front perspective view of a kitchen island showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is another top view thereof, shown without the umbrella for clarity of disclosure;

FIG. 8 is a bottom view thereof;

FIG. 9 is a front view of the kitchen island of FIGS. 1-8 shown in an alternative configuration; and,

FIG. 10 is a rear perspective view thereof.

The dash-dash broken lines illustrate portions of the kitchen island that form no part of the claimed design. The dot-dash broken lines define the bounds of the claimed design and form no part thereof.

1 Claim, 10 Drawing Sheets(56)
